UNITED STATES PATENT OFFICE

JAY K. THOMPSON, OF GARY, INDIANA.

SPACING DEVICE FOR PUNCHING-MACHINES.

1,105,113.

Specification of Letters Patent. Patented July 28, 1914.

Application filed September 22, 1913. Serial No. 791,020.

To all whom it may concern:

Be it known that I, JAY K. THOMPSON, a citizen of the United States, residing at Gary, in the county of Lake and State of Indiana, have invented a new and useful 5 Spacing Device for Punching-Machines, of which the following is a specification.

My invention relates to the class of devices used in connection with a punch in 10 locating the position of the holes to be punched in the web and the flanges of beams, channels and other structural shapes preparatory to fabricating such shapes, and the invention more particularly relates to a 15 spacing device for use in positioning the shape relative to the punch in order to locate the holes without the necessity of marking the location of such holes on the shape preliminary to its being punched.

20 Heretofore in forming the holes in structural shapes it has been the practice to form templets in which holes are bored at the desired distances apart and to then apply the templets to the beams, and mark and center 25 punch the location of the holes on the beams through the medium of the templet after which the holes were punched as marked.

One object of my invention is to provide 30 an improved spacing device having novel means whereby the necessity of making such templets and of marking the beams preparatory to punching the holes therein is avoided and overcome.

Another object of my invention is to provide 35 a spacing device having novel means whereby the location of a series of holes is determined in one direction such as the length of the shape without laying out or marking such location on the shape.

40 A further object of my invention is to provide a beam spacer adapted for use with a punch and having novel means whereby the tape forming part of my improved apparatus is manipulated in the shape marking 45 operations.

Still further objects of my invention will appear as the invention is more fully described hereinafter.

Referring to the accompanying drawings 50 forming part of this specification Figure 1 is a side elevation of a punching machine showing a spacing device as constructed and arranged and applied for use thereon in accordance with my invention. Fig. 2 is an 55 end or front elevation of the apparatus shown in Fig. 1. Fig. 3 is a sectional plan

of the same, the section being taken on the irregular line III—III of Fig. 2 showing the marking tape forming part of my improved spacing device as attached to a beam 60 in the beam punching operations. Fig. 4 is a side elevation of a portion of the apparatus showing the application of my invention in punching the flanges of I-beams.

In the drawings the numeral 2 designates 65 the frame or housing of a beam punch having a bottom anvil block 3 and a reciprocating ram 4, the ram 4 also having an anvil block 5 thereon in which a punch or plurality of punches 6 is adjustably secured. 70 The construction of the punching mechanism, not in itself forming part of this invention, is not further described.

Fastened on the side of the housing 2 at 75 one side thereof is a bent arm 7 having a shaft 8 rotatably secured on its lower end and removably secured on the shaft 8 so as to rotate with this shaft is a drum or spool 9 on which the marking tape 22 is wound and unwound. On the other end of the 80 shaft 8 is a second spool or drum 10 to one of the flanges 11 of which one end of a cord or other flexible connection 12 is secured and the cord 12 extends upwardly and around a pulley 13 which is rotatably mounted on the 85 arm 14 secured to or constructed to form part of the bent arm 7. The cord 12 also passes around a second pulley 15 on the top of the housing 2 and extends downwardly and around the movable pulley 16, to which 90 a counterweight 17 is secured, and then passing upwardly the cord 12 is attached by its other end to the top of the punch housing 2. Also fixed to one side of the punch housing 95 2 is a bent arm 18 on one end of which an index pin or pointer 19 is secured, and attached to this pointer is a guide wheel 20 which is employed to assist in maintaining the tape used in the punching operations in 100 position on the upper face of the shape in which the holes are being punched.

On the opposite side of the punch to that 105 on which the pointer 19 is positioned is a pair of strippers 21 which prevent the beam from rising more than a limited amount when the punches are withdrawn.

In the construction shown in Fig. 4 of the drawings the spacing device is the same as in the preceding figures, and the only change made is in the construction of the anvil 110 blocks 3 and 5 and in the number of punches 6 employed, the construction of Fig. 4 being

primarily intended for use in punching holes in the flanges of beam shapes instead of in the web portion of the beams as in Figs. 1, 2 and 3.

5 Wound upon the spool 9 is a steel tape 22, which preferably differs from the usual steel tape in that it is not graduated in feet and inches, but has plain surfaces. The uppermost surface of the tape is provided with 10 marks at suitable intervals in the length thereof which are spaced the desired distances apart at which it is desired to punch the holes in the length of the beam.

As the gage lines or distance between the 15 parallel rows of holes formed in a beam are usually standard, the punches 6 will be adjusted in the anvil blocks to form the holes on the desired gage lines so that in punching the holes in the beams it is only necessary to 20 locate the holes lengthwise relatively to the ends of the beam being punched.

A series of the tapes 22 will be kept on hand which are variously graduated usually 25 by temporary markings so that by removing the spool 9 with the tape 22 thereon and replacing it with another spool having a tape marked as required, successive beams or lots 30 of beams can be punched with holes of varying spacing. The free end of the tape 22 is provided with a hook portion 23 which is arranged to embrace the end of the beams 24 being punched and which will hold the tape 35 on the beam and cause it to be unwound as the beam is moved lengthwise within the throat of the punching machine in the successive punching operations.

In the operation of my improved apparatus a spool 9 having a tape 22 which is 40 graduated or marked in the desired manner is secured on the shaft 8 so as to rotate therewith. The punches 6 having been adjusted to the desired gage, the hook end 23 of the tape 22 wound upon the spool 9 is caused to engage with the end of a beam 24 which is 45 to be punched. The beam 24 is then moved lengthwise within the throat of the punching machine until the index finger or pointer 19 coincides with the first graduation on the 50 tape and the beam having then been brought to rest, the punching machine is actuated to advance the punches 6 and thereby form a hole or row of holes in the web of the beam 24. The reciprocating ram of the punching machine then being retracted, the beam 24 is 55 moved forwardly until the next graduation on the tape 22, which moves lengthwise with the beam, is in register with the index finger 19 when the machine is again caused to reciprocate the ram 4 and form another series 60 or row of holes in the beam. As the beam is moved lengthwise, from right to left in Fig. 1, the tape 22 is gradually unwound from the spool 9 and this unwinding operation rotates the shaft 8 and causes the cord 12 to 65 be wound upon the spool 10 and as the cord

12 is wound upon this spool, the counterweight 17 is raised or lifted, and in this way the desired tension is maintained on the tape during the punching operations. As the above described operations are repeated

70

the tape is further unwound from its spool 9. When the beam has been punched with the desired number of holes the hook end 23 of the tape 22 is disconnected from the end of the beam 24 and the counterweight 17 then acts to rotate the shaft 8, which turns the spool 10 and winds the tape 22 upon the spool 9 in readiness for another punching operation. The above described operations are then repeated with as many beams as it is desired to duplicate, and as ordinarily in punching structural shapes there is a large number of beams which are exact duplicates as to punching, after one tape and its spool is positioned on the shaft 8 it will be used again and again for a considerable period of time. When it is desired to punch the holes in the beams to a different spacing, the tape on the punch will be removed and a new tape graduated or marked in the desired manner will be substituted therefor and the above described operations will then be again repeated.

80

In using the punching machine of Fig. 4 the operations will be carried out in exactly 95 the same manner as has been described, except that the punches will form the holes in the flanges of the beams instead of the web portion thereof.

90

The advantages of my invention will be 100 apparent to those skilled in the art. By the use of my improved spacing device the necessity of making templets or of marking the holes on the surfaces of the beams preparatory to punching the holes are avoided and 105 overcome. The apparatus is simple and can be applied to existing punches at small cost.

105

Modifications in the construction and arrangement of the parts may be made without departing from my invention as defined in 110 the claims.

110

I claim:—

115

1. In a punching machine, a spacing device comprising in combination an index finger on the punching machine and a graduated tape coöperating therewith to determine the location of holes to be punched, means on the end of the tape engaging with the materials being punched to move the tape therewith, a rotating reel on which the tape is wound and unwound in punching, and means for rotating the reel arranged to yieldingly resist rotation thereof in unwinding the tape from the reel to thereby maintain the tape under tension in the tape unwinding operations.

120

2. In a punching machine, a spacing device comprising in combination an index finger on the punching machine and a graduated tape coöperating therewith to deter-

130

mine the location of holes to be punched, means on the end of the tape engaging with the materials being punched to move the tape therewith, a rotating reel on which the 5 tape is wound and unwound in punching, and means for rotating the reel to wind the tape upon its reel after completing the punching operations.

3. In a punching machine, a spacing device comprising in combination an index finger on the punching machine and a graduated tape coöperating therewith to determine the location of holes to be punched, means on the end of the tape engaging with 10 the materials being punched to move the tape therewith, a rotating reel on which the tape is wound and unwound in punching, and means for rotating the reel arranged to 15 yieldingly resist rotation thereof in unwinding the tape from the reel to thereby maintain the tape under tension in the tape unwinding operations, said means being arranged to rotate the reel and wind the tape 20 thereon after completing the punching operations.

4. In a punching machine, a spacing device comprising in combination an index finger on the punching machine and a graduated tape coöperating therewith to determine the location of holes to be punched, means on the end of the tape engaging with 25 the materials being punched to move the tape therewith, a rotating reel on which the tape is wound and unwound in punching, an 30 arm forming a guide engaging with and holding the tape in position in the tape unwinding operations, and means for rotating the reel arranged to yieldingly resist rotation thereof in unwinding the tape from the 35 reel to thereby maintain the tape under tension in the tape unwinding operations.

5. In a punching machine, a spacing device comprising in combination an index finger on the punching machine and a graduated tape coöperating therewith to determine the location of holes to be punched, means on the end of the tape engaging with 45 the materials being punched to move the tape therewith, a rotating reel on which the tape is wound and unwound in punching, a 50 shaft on which said reel is removably secured to rotate therewith, a second reel on said shaft, a flexible connection on the second reel, and a counterweight on the flexible connection arranged to be lifted by and 55 maintain the tape under tension in the unwinding operations of the tape.

6. In a punching machine, a spacing device comprising in combination an index finger on the punching machine and a graduated 60 tape coöperating therewith to determine the location of holes to be punched, means on the end of the tape engaging with the materials being punched to move the tape therewith, a rotating reel on which the 65 tape is wound and unwound in punching, a shaft on which said reel is removably secured to rotate therewith, a second reel on said shaft, a flexible connection on the second reel, and a counterweight on the flexible 70 connection arranged to be lifted by and maintain the tape under tension in the unwinding operations of the tape, and wind the tape upon its reel when the tape is detached from the material being punched. 75

In testimony whereof, I have hereunto set my hand.

JAY K. THOMPSON.
